UNITED STATES PATENT OFFICE.

EDSON L. BEARDSLEY, OF COLUMBUS, OHIO.

LIFTER.

1,310,594.

Specification of Letters Patent. Patented July 22, 1919.

Application filed February 11, 1918. Serial No. 216,563.

To all whom it may concern:

Be it known that I, EDSON L. BEARDSLEY, a citizen of the United States, residing at Columbus, in the county of Franklin and 5 State of Ohio, have invented certain new and useful Improvements in Lifters, of which the following is a specification.

This invention relates to lifters, and has for its primary object to provide a simple, 10 adjustable and efficient tool for facilitating the removal of the valve structure found in internal combustion engines.

Another object of invention is to improve the construction disclosed in my former 15 Patent No. 1,241,488, granted October 2, 1917, by rendering the construction disclosed in this patent adjustable, in order that the same may be conveniently adapted for engines of various proportions or other 20 structural differences.

A further object of the invention is to provide a lifter designed for use in assisting in removing the springs encircling the valve stems of internal combustion engines. In 25 grinding or replacing these internal combustion engine valves, it is necessary to first remove the spring normally seating the valve from its operative position so as to permit of the removal of the entire valve. 30 Therefore, my invention is so constructed as to be capable of being quickly and conveniently associated with such valve structures and provides means for readily effecting the removal of the springs thereof.

35 A further salient object of the invention resides in a peculiarly formed adjustable cam member, which is arranged to bear upon the valve head and in providing the other extremity of the tool with a removable and 40 adjustable spring elevating leg member, which latter is adapted to encircle the valve stem at a point beneath the spring seat, so that when said cam is actuated, said leg member will be elevated to permit of the 45 removal of said spring seat from the valve stem, and to thereby permit of the removal of the valve structure in its entirety.

With these and other objects in view, as 50 will appear as the description proceeds, the invention consists in the novel features of construction, combinations of elements and arrangements of parts hereinafter fully described in the following description and set forth with particularity in the appended 55 claim.

In the drawings:

Figure 1 is a vertical longitudinal sec-

tional view taken through my approved type of lifter and disclosing the same in its operative position in connection with the 60 valve structure of an internal combustion engine.

Fig. 2 is a transverse sectional view taken through the cam supporting and adjusting mechanism. 65

Fig. 3 is a horizontal sectional view taken along the line 3—3 of Fig. 1.

Fig. 4 is a grouped view disclosing the plurality of sizes of the spring lifting members. 70

Similar characters of reference denote corresponding parts throughout the several views of the drawing.

Referring more particularly to the accompanying drawing, there has been diagrammatically represented the valve supporting portions 1 of an explosive engine, the latter being provided, as usual, with a valve structure consisting of a head 2 and a stem 3. The lower end of the valve is provided with 80 a spring seating washer 4, which is held in a normal position by means of the pin 5 passing through the stem, in order that the spring 6 encircling the stem may be operatively held in position, that is to normally 85 maintain the head 2 within its seat 6. In removing the valve, it is first necessary to remove the pin 5, which releases the operative connection between the spring 6 and the valve stem 3. Subsequent to the removal 90 of this pin, the stem itself may be also removed from the engine portions 1.

It is the means for permitting the removal of the pin 5 with which my invention is particularly concerned, and to this end use is 95 made of a lifter A, the latter consisting essentially of a yoke 7, formed to provide a cam carrying arm 8 and a spring lifting arm 9, the arms 8 and 9 being adjustably connected, as will be hereinafter described, 100 and are preferably formed of U shaped channel iron or of any other suitable material.

The extremity of the arm 8 is provided with an opening 9', which opening aligns 105 with a similar opening formed in a block 10, the latter being integrally formed with the arm 8 or may be welded thereto, as desired. Inserted through these openings is a cam carrying bolt 11, which is provided with a 110 threaded body for the reception of an adjusting nut 12, the latter having a suitable knurled surface. By rotating the nut 12 the bolt 11 may be adjusted vertically as re-

gards the arm 8, for purpose to be presently disclosed. The lower extremity of the bolt 11 is bifurcated to pivotally receive an eccentric or cam lever 13, which is provided with 5 an interval manipulating handle 14 and a flattened valve engaging surface 15, which surface may be brought to bear into flush engagement with the valve 2 by rotating the handle 14. The arm 9 is removably connected with arm 8 through the provision of 10 a horizontally extending transverse bolt 16, which latter is provided with a head 17, adapted to be disposed within the channel of the arm 9. The shank of the bolt 16 extends through an opening 17, formed in said 15 arm 9, and through an elongated slot 18 formed in the lower end of the arm 8. A wear plate 18 encircles the arm 8 and is provided with an opening for the reception of 20 the shank of the bolt 16, and threaded upon the latter is a wing nut 19, which is adapted to be brought into frictional engagement with the plate 18 so as to firmly bind the arms 8 and 9 together. By loosening the nut 25 19, it will be seen that the arms 8 and 9 may be adjusted relatively, and may be maintained in such adjusted positions by the tightening of the bolt 19 into engagement with the plate 18, the elongated slot 18 permitting of the relative movement between 30 said arms 8 and 9.

The lower end of the arm 9 is disposed on a horizontal plane and terminates in a bifurcated end 20, so as to provide a stem receiving slot 21, which slot is sufficiently 35 large to permit the bifurcated extremity 20 to readily receive the valve stem 3, as shown in Fig. 1. My present invention contemplates equipping the tool A with several 40 sizes of arms 9, so that the latter may be applicable to the various sizes of valve stems.

In operation, when it is desired to effect 45 the removal of the valve structure from the engine 1, the arm 9 is so situated that the slot 21 formed therein will encircle the valve stem at a point immediately beneath the washer 4, and the arms 8 and 9 are adjusted vertically so that the cam 13 will engage 50 with the upper surface of the valve 2. The initial adjustment of the arms 8 and 9 to effect a proper positioning of the cam lever as regards the valve 2, is effected through 55 the bolt and nut connection 17 and 19 existing between said arms, and if this adjustment should not prove to be ample, a further adjustment of the cam lever may be effected by rotating the nut 12, so that the vertical position of the bolt 11 may be readily controlled. The adjustments described will insure a proper position of the lifter A as regards the valve structure, moreover, by virtue of the adjustable character of the lifter 60

the same can be adapted to the different makes of explosive engines, this feature having been omitted in my former patent. 65

After the lifter has been thus positioned, in substantially the manner shown in Fig. 1, the valve may be removed by rotating the cam lever 13, so that the surface 15 of the latter will be brought into engagement with the upper surface of the valve 2. This operation, due to the eccentric manner of connecting the lever with the bolt 11, will effect the raising of the arms 8 and 9, to the 70 dotted line position shown in Fig. 1. This permits the washer 4 to be freed from engagement with the pin 5, and due to the fact that pressure has been removed from said pin, the latter may be readily withdrawn 80 from its position within the stem 3. Subsequent to the removal of the pin 5, the cam lever is rocked to its initial position, so that the same may be removed from engagement with the valve structure and to permit of the 85 removal of said structure from the engine 1.

From the foregoing description, taken in connection with the accompanying drawing, it will be apparent that I have provided a lifter of considerable utility and one wherein in a valve may be removed by a simple application and operation of the tool. Through the adjusting mechanism described, the field of utility of the lifter A has been considerably widened, since the tool or lifter may 95 be employed in connection with different types and sizes of explosive engines, and is not limited to one particular type, as is the case in my former patent. 100

What I claim is:

A valve lifter for explosive engines, comprising a substantially L shaped frame member; a lower frame member adjustably and detachably carried by said former member and provided with a slotted valve stem embracing portion, means for elevating and lowering said extremity, comprising a threaded rod slidably mounted in an opening formed in the free end of said L shaped member, a nut threaded upon said rod, and a cam lever pivotally mounted in a slot formed in the lower end of said bolt and operable when oscillated in one direction to force said nut in engagement with the free end of said L shaped member so as to effect the elevation of said valve stem engaging extremity, and when oscillated in a reverse direction to permit of the lowering of said extremity. 105 110 115

In testimony whereof I affix my signature 120 in presence of two witnesses.

EDSON L. BEARDSLEY.
